(57) **CLAIM**

The ornamental design for "biodegradable food service container," as shown and described.

DESCRIPTION

FIG. 1 is a perspective view of the two-piece biodegradable food service container of the present invention.

FIG. 2 is a perspective view of the first piece of the container shown in FIG. 1.

FIG. 3 is a perspective view of the second piece of the container shown in FIG. 1.

FIG. 4 is a top view of the container shown in FIG. 1.

FIG. 5 is a side view of the container shown in FIG. 1, the opposite side being the mirror image thereof.

FIG. 6 is an end view of the container shown in FIG. 1, the opposite end being the mirror image thereof.

FIG. 7 is a bottom view of the container shown in FIG. 1.

FIG. 8 is a top view of the first piece shown in FIG. 2.

FIG. 9 is a side view of the first piece shown in FIG. 2, the opposite side being the mirror image thereof.

FIG. 10 is an end view of the first piece shown in FIG. 2, the opposite end being the mirror image thereof.

FIG. 11 is a bottom view of the first piece shown in FIG. 2.

FIG. 12 is a top view of the second piece shown in FIG. 3.

FIG. 13 is a side view of the second piece shown in FIG. 3, the opposite side being the mirror image thereof.

FIG. 14 is an end view of the second piece shown in FIG. 3, the opposite end being the mirror image thereof; and,

FIG. 15 is a bottom view of the second piece shown in FIG. 3.

1 Claim, 5 Drawing Sheets
